CLAIM

The ornamental design for a headshell as shown and described.

DESCRIPTION

FIG. 1 is a top perspective view of a headshell; FIG. 2 is a bottom perspective view of the headshell; FIG. 3 is a front elevational view of the headshell; FIG. 4 is a rear elevational view of the headshell; FIG. 5 is a top plan view of the headshell; FIG. 6 is a bottom plan view of the headshell; FIG. 7 is a right side elevational view of the headshell; FIG. 8 is a left side elevational view of the headshell; FIG. 9 is an enlarged sectional view of the headshell taken in the direction of line 9-9 of FIG. 3; FIG. 10 is an enlarged sectional view of the headshell taken in the direction of line 10-10 of FIG. 6; FIG. 11 is an enlarged sectional view of the headshell taken in the direction of line 11-11 of FIG. 8; and, FIG. 12 is an enlarged sectional view of the headshell taken in the direction of line 12-12 and 12-12 of FIG. 11. The evenly dashed broken lines in FIGS. 9 to 12 depict portions of the headshell that form no part of the claimed design. The dot dot dash lines in FIG. 12 enclose an enlarged portion of the headshell and form no part of the claimed design.

1 Claim, 12 Drawing Sheets
